UNITED STATES PATENT OFFICE.

EUGENE P. SMITH, OF SHELBY, OHIO.

PIPE-WRENCH.

1,288,719.

Specification of Letters Patent. Patented Dec. 24, 1918.

Application filed April 11, 1918. Serial No. 227,937.

To all whom it may concern:

Be it known that I, EUGENE P. SMITH, a citizen of the United States, residing at Shelby, in the county of Richland and State of Ohio, have invented certain new and useful Improvements in Pipe-Wrenches, of which the following is a specification.

This invention is a wrench and has a special reference to that class of wrenches commonly known as pipe wrenches.

One object of this invention is the production of a pipe wrench wherein a movable jaw may be quickly and easily moved to an adjusted position and then held against accidental movement.

Another object of this invention is the production of a pipe wrench wherein a cam engages the movable jaw for firmly holding the same in engagement with a rack block, thus holding the jaw against movement after being moved to an adjusted position.

Another object of this invention is the production of a pipe wrench wherein there is provided a pivotally supported spring-actuated slide block, this slide block engaging the shank of the movable jaw for forcing the same from engagement with the rack block, when such movement permits by prior actuation of the cam, thus permitting the movable jaw to be moved to a desired position.

Broadly stated, this invention consists of a fixed jaw having a handle extending therefrom, a housing pivotally mounted upon said handle, a rack block fixedly carried by said housing, a spring-actuated slide block carried by said housing, a sliding jaw having a shank provided with rack teeth, and a cam carried by said housing and engaging one side edge of the shank of said movable jaw, thus allowing the shank to be moved into engagement with the rack block for holding the jaw against accidental movement, although said slide block will engage said shank for urging the same from engagement with said rack block when the cam has been turned to a necessary position.

With these and other objects in view, this invention consists of certain novel combinations, constructions and arrangement of parts as will be hereinafter fully described and claimed.

One practical form of construction and assembly of the present invention will be

hereinafter described and is illustrated in the accompanying drawing, in which—

Figure 1 is a side elevation of the wrench, partly in section, with one plate and the spacing block of the housing removed, illustrating the wrench in condition for permitting of movement of the movable jaw.

Fig. 2 is a view similar to Fig. 1, showing the wrench in a locked condition or when the movable jaw is held in an adjusted set position, and

Fig. 3 is a section taken on the line 3—3 of Fig. 1, looking in the direction of the arrows.

In the preferred embodiment of the present invention, about to be described, 5 designates the handle having a fixed jaw 6 thereon, this jaw 6 being serrated, as indicated at 7. The handle 5 is provided with an enlargement 8 upon one side thereof and the pivot lugs 9 extend from opposite sides of this enlargement 8.

The housing comprises a pair of side plates 10 carried in spaced relation with respect to each other and a block 11 is interposed between the rear portions of the side plates 10, as illustrated in Fig. 3. The rivets 12 pass through the side plates and also through the block 11, thus holding these elements in fixed engagement with each other. The forward portions of these side plates of the housing are spaced apart to receive the operating elements of the wrench as is obvious from an inspection of Fig. 3. The lugs 9 of the enlargement 8 of the handle 5 are carried by the side plates 10 of the housing, thus pivotally supporting the handle and the fixed jaw upon this housing. Projections 13 extend from the front edges of the plates 10 and carry a bearing rivet 14, as shown in Figs. 1 and 2. The flat spring 15 is fixedly carried by the screw 16 upon the fixed jaw and the free end of this spring 15 bears upon the bearing rivet 14 for normally urging the handle 5 in one direction as will be hereinafter more fully specified.

The rack block 17 is provided with a pocket 18 in one side thereof into which the enlargement 8 of the handle 5 extends. This rack block 17 is held in fixed engagement with the housing by rivets 19, these rivets 19 passing through the side plates 10 of the housing and also through the rack block 17. This rack block 17 is provided with rack teeth 20 upon one side thereof, while it will be noted that this rack block 17 terminates

short of one side of the housing. This rack block however, is carried within the housing for the greater portion of its distance, as will be seen by referring to Figs. 1 and 2.

5 The slide block 21 is of an elongated construction and has a squared-face bearing lug 22 adjacent its inner end. This slide block 21 is pivotally mounted upon the rivet 23 passing therethrough and carried by the side 10 walls 10 of the housing. The slide block 21 is carried in direct alinement with the rack block 17 to engage the shank of the movable jaw to be hereinafter specified. This slide block 21 is normally urged in one direction 15 by the tension of the coil spring 24, this coil spring 24 having one end carried within the pocket 25 formed in the handle 5, while the opposite end of this coil spring bears against the slide block 24.

20 The movable jaw 26 has a serrated inner surface 27, while the shank 28 extends from this jaw. This shank 28 is provided with teeth 29 upon its inner side edge, although the rear edge 30 of the shank 28 is straight 25 throughout its entire length. The shank 28 extends through the housing to carry the movable jaw 26 in alinement with the fixed jaw 6. It is therefore obvious that when it is desired, the serrated surface 27 of the 30 movable jaw 26 will move toward the serrated surface of the fixed jaw 6, thus moving the movable jaw to an adjusted position to provide sufficient space for the accommodation 35 of a pipe between the jaws. A pin 31 extends through the outer end of the shank 28 and this pin holds the shank from being accidentally withdrawn from engagement with the housing, for upon the shank being moved to a certain position with respect to 40 the housing, the pin 31 will engage the housing and thus limit further movement of the shank in one direction.

The cam 32 is headed as indicated at 45 and extends through the housing as shown clearly in several figures of the drawing. This cam 32 is cut away to form a flat bearing face 34, while the remaining surface adjacent the flat face is rounded as indicated at 50 35. This cam 32 extends beyond the outer surface of the housing and has the lever 36 secured thereto in any suitable manner, so that when the lever is swung it will impart rotary motion to the cam.

When this device is in use, the lever 36 is 55 swung outwardly to the position indicated in full lines in Fig. 1, thus causing the flat face 33 of the cam to engage the rear straight edge 30 of the shank 28 of the movable jaw 26. At this time the slide block 21 will be 60 bearing upon the side edge of the shank 28 which has the teeth 29 and owing to the coil spring 24 urging this slide block 21 in one direction, this slide block will urge the shank 28 into engagement with the flat face 34 of the cam 32. This shifting movement of the

shank will cause the teeth of the shank to disengage the teeth of the rack block 17, thus allowing the movable jaw to be shifted to a desired adjusted position. After this action the lever 36 is swung around to move 70 the flat surface 34 of the cam from engagement with the rear straight edge 30 of the shank 28, thus causing the broadest diameter of the cam to be engaged with the shank and hold the shank in engagement with the rack 75 block 17. Therefore, it is obvious the shank will be held against further movement and the movable jaw will therefore be held in adjusted position with respect to the fixed 80 jaw. Owing to the pivotal support of the handle 5, it is obvious the handle may pivot in the direction of the slide block, thus causing a pipe to be gripped between the two jaws, to be more firmly held. It will be noted however, that the pivotal movement of 85 the handle upon the housing will be limited by engaging the bearing lug 22 of the slide block 21 upon one side of the handle as illustrated in Fig. 2.

As this bearing lug is in direct alinement 90 with the rivet 23, it will be seen that the handle will be against further swinging movement independent of the remaining elements of the wrench and thus prevent injury to the elements of the wrench. However, a 95 firm bearing is provided for the handle for assisting in the rotation of the pipe gripped by the wrench.

When it is desired to again adjust the sliding or movable jaw, the lever is swung 100 outwardly to cause the slide block to move the shank from engagement with the rack block thus permitting movement of the movable jaw.

From the foregoing description it will be 105 seen that a very efficient pipe wrench has been produced which may be easily adjusted by the movement of the lever and then by the subsequent shifting of the movable jaw, after which action the lever may be returned 110 to its normal position to extend in an out-of-the-way manner, whereby the shank of the movable jaw will be again held in the locked position for preventing accidental 115 movement of the movable jaw.

The foregoing description and the drawings have reference to what may be considered the preferred, or approved, form of my invention. It is to be understood that I 120 may make such changes in construction and arrangement and combination of parts, materials, dimensions, et cetera, as may prove expedient and fall within the scope of the appended claims.

Having thus fully described my invention, 125 what I claim as new and desire to secure by Letters Patent, is:—

1. In a wrench of the class described, the combination of a fixed jaw having a handle 130 extending therefrom, a housing connected to

5 said fixed jaw and handle, a rack block carried by said housing, a slide block carried by said housing, a movable jaw having a shank extending through said housing, 5 means for releasably holding said shank in engagement with said rack block for holding said movable jaw in an adjusted position and said last mentioned means being adapted to release said shank from a set position, 10 whereupon said slide block will move said shank from engagement with the rack block for allowing the movable jaw to be shifted.

2. In a device of the class described, the combination of a fixed jaw having a handle 15 extending therefrom, a housing connected to said jaw and handle, a rack block carried by said housing, a slide block pivotally mounted upon said housing, means for urging said slide block in one direction, a movable jaw having a shank extending through said housing, a cam carried by said housing, means for shifting said cam, thus causing said shank to be held in engagement with said rack block for holding the jaw in 20 an adjusted condition, and said cam being adapted to move, whereupon said slide block will shift said shank from engagement with the rack block for permitting the movable jaw to be shifted.

30 3. In a wrench of the class described, the combination of a fixed jaw having a handle extending therefrom, a housing connected to said fixed jaw and handle, a rack block carried by said housing, a movable jaw having 35 a shank extending through said housing, means for releasably holding said shank in engagement with said rack block for holding said movable jaw in an adjusted position, said means being adapted to release 40 said shank from a set position, and means for moving said shank from engagement with the rack block for allowing the movable jaw to be shifted without interference.

4. In a device of the class described, the combination of a fixed jaw having a handle 45 extending therefrom, a housing connected to said jaw and handle, a rack block carried by said housing, a movable jaw having a shank extending through said housing, a cam 50 carried by said housing, means for shifting said cam, thus causing said shank to be held in engagement with said rack block for holding the movable jaw in an adjusted position, said cam being adapted to move to release the shank from a set position, and 55 means for shifting said shank from engagement with the rack block for permitting the removable jaw to be freely shifted.

5. In a wrench of the class described, the 60 combination of a fixed jaw having a handle

extending therefrom, a housing connected to said fixed jaw and handle, a rack block carried by said housing, a movable slide block carried by said housing, means for urging said slide block in one direction, a 65 movable jaw having a shank extending through said housing, means for releasably holding said shank in engagement with said rack block for holding said movable jaw in an adjusted position, said last mentioned 70 means being adapted to release said shank from a set position, whereupon said slide block will move said shank from engagement with the rack block for permitting the removable jaw to be shifted. 75

6. In a wrench of the class described, the combination of a fixed jaw having a handle extending therefrom, a housing connected to said fixed jaw and handle, a rack block carried by said housing, a slide block pivotally mounted upon said housing, a spring engaging said slide block for normally urging the same in one direction, a movable jaw having a shank extending through said housing, means for releasably holding said 80 shank in engagement with said rack block, thus holding said movable jaw in an adjusted position, said means being adapted to release said shank from a set position, whereupon said slide block will move said 85 shank from engagement with the rack block, thus permitting the movable jaw to be freely shifted.

7. In a device of the class described, the combination of a fixed jaw having a handle 95 extending therefrom, a housing connected to said jaw and handle, a rack block carried by said housing, a slide block pivotally mounted upon said housing, said handle having a socket in alignment with said slide 100 block, a coiled spring carried within said socket and extending into engagement with said slide block for normally urging the slide block in one direction, a movable jaw having a shank extending through said 105 housing, a cam carried by said housing, means for shifting said cam, thus causing said handle to be held in engagement with said rack block, thus holding the jaw in an adjusted position, and said cam being adapted to move, whereupon said slide block will swing to shift said shank from engagement with the rack block, thus permitting the 110 movable jaw to be easily shifted.

In testimony whereof I affix my signature 115 in presence of two witnesses.
